[57] CLAIM

The ornamental design for a compact disc organizer, as shown and described.

DESCRIPTION

FIG. 1 is a perspective view showing the front design of the compact disc organizer;
FIG. 2 is a top end view of the FIG. 1 organizer;
FIG. 3 is a bottom end view of the FIG. 1 organizer;
FIG. 4 is a right end view of the FIG. 1 organizer;
FIG. 5 is a left end view of the FIG. 1 organizer;
FIG. 6 is a rear view of the FIG. 1 organizer; and,
FIG. 7 is a perspective view showing the organizer in a folded condition, attached to a vehicle sun visor, it being understood that the broken lines are for illustrative purposes only and form no part of the claim.
